CHAIN STRUCTURE

Donald J. McIntosh and Mitchell Smith, Detroit,
Mich.; said McIntosh assignor to said Smith

Application June 13, 1949, Serial No. 98,735

5 Claims. (Cl. 74—254)

1

The present invention relates to chain structure and more particularly to chain structure designed to facilitate separation between links of a sprocket chain.

The present invention is a continuation-in-part of our prior copending application, Serial No. 8,664, filed February 16, 1948.

It is an object of the present invention to provide a chain of sprocket type adapted to be separated between adjacent links thereof by a simple operation.

More specifically, it is an object of the present invention to provide a chain of the character described having alternating pairs of inside and outside link plates which are pivotally interconnected by pivot pins constructed and arranged to be separable from the chain when adjacent pairs of inside and outside link plates are disposed at a particular angularity with respect to each other.

More specifically, it is an object of the present invention to provide a chain of the character described employing alternating pairs of inside and outside link plates, each of which is provided with openings for the reception of headed pivot pins, the pivot pins being held against rotation with respect to the inside plates in use and having laterally extended portions at their ends adapted to serve as stops against removal of the pins except when the adjacent pairs of inside and outside link plates are disposed at a particular angularity different from any which will be encountered in use.

Other objects and features of the invention will become apparent as the description proceeds, especially when taken in conjunction with the accompanying drawings, wherein:

Figure 1 is an exploded view of a single outside link plate and the associated inside link plates.

Figure 2 is a fragmentary side elevation of a portion of an assembled chain.

Figure 3 is a perspective view of one form of pivot pin.

Figure 4 is a perspective view of a somewhat modified form of pivot pin.

Figure 5 is a side elevation of a portion of a chain constructed in accordance with the present invention.

Figure 6 is a fragmentary perspective view of yet another modified form of pivot pin.

Figure 7 is an exploded view showing the pivot pin of Figure 6 located in the inside link plates and the outside link plate in position to be assembled therewith.

2

Referring now to Figures 1-5 the chain structure is illustrated as comprising a first pair of inside link plates 10 and 11, a second pair of inside link plates 12 and 13, and a pair of outside link plates 14 and 15 extending between the pairs of inside link plates. A pivot connection is established between each adjacent pair of link plates by a pivot pin 20 which as illustrated in Figures 1, 2, 4 and 5 is provided with an enlarged central portion 22, reduced neck portions 24 adjacent each end, and laterally extending ears or keys 26 at opposite ends thereof.

Each of the inside link plates 10, 11, 12 and 13 is provided with an opening 30 which is generally circular in shape and of a size to interfit with the reduced cylindrical neck portion 24 of the pivot pin. The openings 30 in the inside link plates also include lateral extensions 32 which will accommodate and permit passage therethrough of the keys 26 provided on the pivot pins.

In like manner, the outside link plates 14 and 15 are provided adjacent the ends thereof with openings 34 which are of generally circular shape and adapted to interfit with the reduced cylindrical neck portions 24 of the pivot pins. Openings 34 also include lateral extensions 36 to permit passage of the key portions 26 of the pivot pins.

In Figure 1 the inside link plates are shown as having the pivot pins 20 assembled therein with the laterally projecting portions of the keys 26 in registry with the lateral extensions 32 of the openings 30. A link plate 15 is illustrated in position to be assembled over the outwardly projecting ends of the pivot pins. It will be appreciated that when the link plate 15 (and the corresponding link plate 14 at the opposite side of the chain) has been assembled over the projecting end of the pivot pin, that portion of the chain may be straightened so that the pairs of inside and outside link plates are in substantial alignment. The inside link plates 20 are adapted to retain the pivot pins 20 against rotation therein and this may be accomplished in any one of several manners, thus for example, the opening 30 in the inside link plates may be such that a press fit results between such openings and the reduced cylindrical neck portion 24 of the pins. A modified arrangement will subsequently be described.

At all events when the adjacent pairs of link plates each constituted by a pair of link plates, is brought into substantial alignment, it will be readily apparent that the key 26 will extend transversely with respect to the axis of the ex-

tensions 36 provided in the openings 34 of the outside link plates. Thus the outside link plates 15 cannot be removed until the parts have been brought into the oriented position best illustrated in Figure 1.

The pin illustrated in Figure 3 may be substituted for the pin illustrated in Figure 4. This pin differs therefrom primarily in that the entire length of the pivot pin 40 is of uniform cylindrical shape except for the laterally projecting keys 42 provided at each end. In this instance, inside link plates 10, 11, 12 and 13 are preferably retained in separated position in the assembled chain by virtue of cylindrical sleeves interposed over the intermediate cylindrical portion 48 of the pins and abutting against the inner surfaces of plates 10 and 11 on the one hand and plates 12 and 13 on the other hand.

Also if desired, similar cylindrical sleeves such as shown at 41 in Figure 5 may be provided over the intermediate cylindrical portion 22 of the pins 20 and it will be observed that the ears 26 of the pins 20 do not extend outwardly beyond the projected cylindrical surface 22, so that such sleeves may be slipped over the pin 20 after it has been completed.

Referring now to Figures 6 and 7 there is illustrated a modified construction in which the pivot pin 50 is provided having a central cylindrical portion 52, which may if desired support a cylindrical bearing sleeve (not shown). At the ends of the intermediate cylindrical portion 52, the pins 50 are provided with reduced neck portions 54 which are of cylindrical shape for their major extent, but which are provided with non-circular surfaces 56 for a purpose which will presently appear. Conveniently, the surfaces 56 may represent flats provided which lie within the generally cylindrical configuration of the neck portion 54. Outwardly beyond the reduced neck portion 54 the pins 50 are provided with laterally extending ears 58.

Referring now to Figure 7 the inside link plates 60 are each provided with openings 62 which are of generally circular shape so as to interfit with the cylindrical portion of the necks 54. However, openings 62 also include lateral extensions 64 to permit passage of the ear 58 therethrough and further include surface portions 66 adapted to interfit with and cooperate with the surface portions 56 on the neck of the pins so as to prevent rotation of the pins in the inside links. On the other hand, the outside link plates 70 are provided with openings 72 which are of circular shape with the exception of lateral extensions 74 adapted to permit passage therethrough of the ears 58. The openings 72 do not have non-circular surface portions such as the portions 66 and accordingly, the outside plates 70 are rotatable on the cylindrical portion of the reduced necks 54.

The parts illustrated in Figures 6 and 7 are assembled in precisely the same manner as those previously described except that due to the interfitting configuration of the reduced necks of the pivot pins and the openings adjacent the ends of the inside plates, rotation between these elements is effectively prevented while at the same time the parts may be readily separated.

The drawings and the foregoing specification constitute a description of the improved chain structure in such full, clear, concise and exact terms as to enable any person skilled in the art to practice the invention, the scope of which is indicated by the appended claims.

What we claim as our invention is:

1. A chain comprising a pair of elongated inside plates having openings adjacent their ends, said openings being of circular shape and including lateral extensions therein, a pair of elongated outside plates for attachment in overlapping relation to the ends of said inside plates, said outside plates having openings adjacent their ends of identical shape to the openings in said inside plates but which openings have the laterally extensions disposed at a substantially different angle with respect to the longitudinal axis of said outside plate from the similar angle of said inside plates, pins having intermediate cylindrical portions fitting within the circular portions of the openings in both of said plates and retained against rotation in said inside plates, said pins having laterally extending ears shaped to pass through the extensions in said openings, said pins being retained with their ears out of registry with the extensions in said outside plates when said plates are in substantial alignment.
2. In a chain, a pair of elongated link plates having overlapping ends, like openings in said overlapping ends disposed to match when said plates are out of alignment, each of said openings comprising a circular portion having a lateral extension, a connecting pin in said openings having a lateral extension at one end shaped to pass through the lateral extensions in said openings when in registry therewith and to serve as a retainer when out of alignment therewith, and means retaining said pin against rotation in one of said openings.
3. A roller chain comprising end overlapping pairs of link plates pivoted together, the overlapping ends of said pairs of plates having registering pin receiving openings therein, pivot pins receivable in said openings comprising a central cylindrical bearing portion, reduced necks adjacent the ends, and heads comprising laterally extending ears beyond said necks, the ends of said ears lying within the projections of the cylindrical central portions, said necks having cylindrical surfaces and depressed locking surfaces, the openings in the innermost pair of link plates having lateral extensions to pass the lateral projections of said heads and edge surfaces engageable with the depressed locking surfaces of said pins to prevent rotation of said pins in said inner plates, the openings in said outer plates being circular and having lateral extensions to pass the lateral projections of said heads when said pairs of plates are out of alignment.
4. A roller chain comprising end overlapping pairs of link plates pivoted together, the overlapping ends of said pairs of plates having registering pin receiving openings therein, pivot pins receivable in said openings comprising a central cylindrical bearing portion, reduced necks adjacent the ends, and heads comprising laterally extending ears beyond said necks, the ends of said ears lying within the projections of the cylindrical central portions, said necks having cylindrical surfaces and depressed locking surfaces, the openings in the innermost pair of link plates having lateral extensions to pass the lateral projections of said heads and edge surfaces engageable with the depressed locking surfaces of said pins to prevent rotation of said pins in said inner plates, the openings in said outer plates being circular and having lateral extensions to pass the lateral projections of said heads when said pairs of plates are out of alignment, said chain including cylindrical sleeves received over the

central cylindrical bearing portions of said pins, said pins including the heads thereon being freely movable through said sleeves on assembly.

5. A roller chain comprising end overlapping pairs of link plates pivoted together, the overlapping ends of said pairs of plates having registering pin receiving openings therein, pivot pins receivable in said openings comprising a central cylindrical bearing portion, reduced necks adjacent the ends, and heads comprising laterally extending ears beyond said necks, the ends of said ears lying within the projections of the cylindrical central portions, said necks having cylindrical surfaces, the openings in the innermost pair of link plates having lateral extensions to pass the lateral projections of said heads and edge surfaces engageable with the surfaces of said pins to prevent rotation of said pins in said inner plates, the openings in said outer plates being

5

circular and having lateral extensions to pass the lateral projections of said heads when said pairs of plates are out of alignment, said chain including cylindrical sleeves received over the central cylindrical bearing portions of said pins, said pins including the heads thereon being freely movable through said sleeves on assembly.

DONALD J. McINTOSH.
